[57]**CLAIM**

The ornamental design for a non-concealed binding fastener, as shown and described.

DESCRIPTION

FIG. 1 is a perspective view of a non-concealed binding fastener showing my new design, the ring binding structure and the binder cover depicted by means of broken lines have been shown for illustrative purposes only and form no part of the claimed design;

FIG. 2 is a second perspective view;

FIG. 3 is a top plan view;

FIG. 4 is a bottom plan view;

FIG. 5 is a side elevational view;

FIG. 6 is a perspective view of a second embodiment of my design of FIG. 1;

FIG. 7 is a top plan view of FIG. 6;

FIG. 8 is a bottom plan view of FIG. 6; and,

FIG. 9 is a side elevational view of FIG. 6.
